FREDERICK W. SCHULTZ AND JOHN A. WILSON, OF BALTIMORE,
MARYLAND.

Letters Patent No. 83,885, dated November 10, 1868.

IMPROVEMENT IN STEAM-HEATERS.

The Schedule referred to in these Letters Patent and making part of the same.

To all whom it may concern:

Be it known that we, FREDERICK W. SCHULTZ and JOHN A. WILSON, of the city of Baltimore, in the county of Baltimore, and State of Maryland, have invented a new and improved Mode of Warning and Ventilating Buildings; and that the following is a full, clear, and exact description of the same, reference being had to the accompanying drawings, making a part of this specification, in which—

Figure 1 represents a perspective view of the apparatus.

Figure 2 represents a vertical section through the same.

Figure 3 represents a top view of the circulating coil.

Similar letters of reference, where they occur in the drawings, denote like parts of the apparatus in all the figures.

The nature of our invention relates to the providing of a suitable water-back to a kitchen-range, from which the heated water passes into a receptacle or boiler, placed immediately adjacent to the range, and from which the heated water passes through a circulating coil, placed in some convenient position, and so arranged that the water will circulate freely and rapidly when giving out its latent heat.

Our invention further relates to the use of a draught-flue, taken from the top of the building and brought down to the bottom of the coil, this draught-flue being furnished at the bottom with a valve, to prevent any return upwards of the draught, and at the top with a turn-cap, with the wings so placed as to keep the mouth of the turn-cap always before the wind.

We may also use a draught-flue, taken from the outside of the building, at the nearest point to the coil, which flue is also furnished with a valve, to prevent any return-draught. Both the upper and lower flues are brought opposite each other in the air-tight box which encloses the coil, from which box the heated air is taken to the different portions of the building by means of ordinary flues or pipes.

To enable others skilled in the art to make and use our invention, we will proceed to describe the same with reference to the drawings.

A represents the room or building where our apparatus is used. B is the range, which is furnished with the water-back C, which will present to the fire the greatest amount of heating-surface possible. It is for this purpose extended upwards at C, and forms, for a short distance, the flue of the range.

To this portion C is attached a pipe, a, (which is generally two and a half inches in diameter,) which carries the heated water to the boiler D, which acts as a receptacle for the hot water.

From the top of this boiler D the pipe b carries the hot water to the heating-coil E, which is composed of a series of cast-iron pipes, so made that the outer surface of each pipe presents the appearance of a screw, with a number of threads around it. Each thread is

raised about three-fourths of an inch from the body of the pipe, and the threads are about half an inch apart at the top, thus presenting sharp angles at the top and bottom, and a large heating-surface.

Each pipe (except the top and bottom pipes of the coil) is cast with the half of a return-bend at each end. The upper half, d, of the return-bend is dressed of a convex form, and the lower half, e, of the return-bend is dressed concave, between which is introduced the soft washer f, which makes the joint perfectly watertight, when the parts are brought together by the rod h and oblong clamp or washer i, against which the nuts k act on the rod h.

Each half bend is cast with a projection, l, to hold the rod h or clamp i in position, and prevent them from slipping off. This same projection l serves also to retain in place the saddles m, which are used to retain the pipes in proper position, when a large number is used, one above the other, the rod h' and clamp i holding them all together.

The upper pipes of the coil are all attached to the pipe F, which receives the hot water from the pipe b, while the lower row of pipes in the coil is attached to the pipe G, which returns the water, which has been chilled in the coil, back to the range B and water-back C, by means of the return-pipes n and p.

In the construction of the heating-coil E, the sections are placed horizontally together, the threads or angles nearly touching, allowing but small spaces through which the air can pass, thus securing the full benefit of all the heating-surface. Between the tiers of sections there is left a wider space, where the heated air can expand and pass between the tiers above.

The coil E is placed in an air-tight box, at the bottom of which enters the cold-air flue H, which brings the cool, pure air from the top of the building, where it enters the flue H, through the mouth of the revolving cap I, the latter being always kept before the wind by the wings g.

At the bottom of the air-flue H, where it enters the air-tight box of the heating-coil E, is placed a valve, r, opening inwards, to admit the cold air to the coil E, but preventing any returning draught. On the opposite side of the air-tight box, enclosing the heating-coil E, there is the air-flue H', which has a valve, r', opening inwards, to admit the cold air to the coil E, and prevent any return draught. The object of this air-flue H' is to supply air to the heating-coil only when, by reason of the shifting of the wind, the revolving cap I is not operating.

The operation of our heating-apparatus is as follows:

The cold water is admitted to the boiler D in the ordinary way, from which it passes through the pipe p to the water-back C, from which it rises in the upper portion C, where it is also heated. It passes then through the pipe a to the upper part of the boiler D, and from there, by means of the pipe b, to the coil E, of which the screw-shaped sections getting heated,

transmit the heat of the water to the air which has been brought from the flue H, through the opening closed by the valve r, when the chilled water returns, by means of the pipe n, to the bottom of the boiler D, from which it is again transferred, by the pipe p, to the water-back C, to be heated again. In this manner a continuous flow of hot water is passed through the coil E, and a continuous flow of fresh and pure air is introduced round the coil, where it is warmed, and from which it is carried, by means of ordinary flues or pipes, through the building, to warm and ventilate it.

In this manner the apparatus is self-acting, and requires no further attention than a common range. Hot water can also be drawn from the boiler for the use of the house, without affecting the operation materially.

Having thus fully described our invention,

What we claim therein as new, and desire to secure by Letters Patent, is—

1. In combination with the elevated water-back, the

boiler and steam-coils, made and arranged to operate substantially as and for the purpose set forth.

2. Also, the screw-thread form of the coil-pipes, when so arranged in series that the threads of the adjacent pipes shall nearly or quite touch each other, and leave openings between them for the air to pass through and become heated, by impinging upon the extended surface, substantially as described.

3. Also, in combination with a hot-water heater, the introduction of the cold air from the top or upper part of the house, by means of a turn-cap, air-flue, and valve, substantially as described.

4. Also, the supplemental air-flue and valve to furnish air momentarily, while the turn-cap may be veering, substantially as described.

F. W. SCHULTZ.
JOHN A. WILSON.
